Primary Examiner — Karen S Acker*Assistant Examiner* — Wendy Arminio(74) Attorney, Agent, or Firm — Ferdinand IP, LLC(57) CLAIM

The ornamental design for a bag with fabric pattern, as shown and described.

DESCRIPTION

FIG. 1 is a front perspective view of a bag with fabric pattern showing my new design;

FIG. 2 is a front side elevational view thereof;

FIG. 3 is a back side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed lines in the drawings are included for purposes of illustrating the portions of the bag with fabric pattern that form no part of the claimed design.

The solid lines with dashes in the drawings represent stitching of the fabric pattern and are part of the claimed design. The long-short dash lines indicate the boundaries of the claimed design and are not a feature of the design.
